UNITED STATES PATENT OFFICE.

HOMER G. KELLOGG, OF DETROIT, MICHIGAN, ASSIGNOR TO MOTOR PRODUCTS CORPORATION, OF DETROIT, MICHIGAN, A CORPORATION OF NEW YORK.

FINISH-STRIP ASSEMBLY.

Application filed August 15, 1927. Serial No. 213,081.

This invention relates to a finish strip assembly and more particularly to a combined finish strip and drip rail having means for securing a trimming material in place.

5 The several objects, advantages and novel details of construction of this invention will be made more apparent as this description proceeds, especially when considered in connection with the accompanying drawings 10 wherein:

Figure 1 is a fragmentary perspective view of a finish strip assembly constructed in accordance with this invention, and

15 Figure 2 is a vertical section of the structure illustrated in Figure 1.

Referring now particularly to the drawings wherein like reference characters indicate like parts, it will be noted that there is illustrated member 10 which may be a 20 portion of the frame or body of the motor vehicle or other support to which this finish strip assembly is to be attached. The reference character 11 indicates trimming material which extends over the face of the support 25 port 10 and is adapted to be secured thereto in a manner to be described more fully hereinafter.

One face of the support 10 is recessed longitudinally thereof as indicated at 12. 30 Secured to the recessed face of the support 10 is a face plate 13 provided with a depression forming a recess 14 which fits in the recess 12 formed in the support 10. The trimming material 11 overlies this face plate 35 13 and extends down into the recess 14. The provision of the recess 14 provides a shoulder 15 over which the trimming material extends.

Secured within the recess 14 is an anchorage strip 16 developed from a single strip of material and bent to form support engaging portions 17 and an angularly extending lip or projection 18. The anchorage strip is apertured at suitable intervals throughout 45 its length for the reception of securing elements 19 which pass therethrough and into the support 10.

When the anchorage strip is secured in place the lip or projection 18 is opposed to the shoulder 15 of the recess 14 and cooperates therewith to grip the trimming material therebetween. Thus the trimming material may be brought downwardly over the support 10 so as to overlie the recess 14 50 and when thereafter the anchorage strip 16

is secured within the recess the trimming material will be stretched by being forced into the recess 14 and will be gripped between the shoulder 15 and the flange or projection 18 of the anchorage strip. 60

The reference character 20 indicates generally a molding strip which is developed from a single strip of material the intermediate portion of which is bent upon itself as indicated at 21 to provide a double wall 65 thickness which is shaped to form a drip trough 22. The edges of the molding strip are bent to form opposed inwardly extending open return-bent portions 23 which are adapted and capable of snap engagement 70 with the edges of the anchorage strip 16. The molding strip 20 is snapped into engagement with the anchorage strip by pressing the molding strip thereagainst whereupon the return-bent edges 23 snap over the 75 edges of the anchorage strip as will be obvious.

While the facing plate 13 has been illustrated and described for use in connection with the support 10 and while this construction is found to be satisfactory and efficient in actual use, nevertheless, it will be immediately obvious that the use of this plate 13 is not absolutely essential. Furthermore it is not always necessary to locate the anchorage strip 16 in a recess either in the support 80 10 or in the facing plate 13. On the other hand, it is important only that the equivalent of the shoulder 15 be provided with which the extension or flange 18 of the anchorage strip may cooperate. 85 90

As a consequence, while one specific embodiment of the invention has been illustrated and described herein somewhat in detail it will be readily apparent to those 95 skilled in this art that various changes in the details of construction herein illustrated may be made without departing from the spirit and scope of this invention and to this end reservation is made to make such changes 100 as may come within the purview of the accompanying claims.

What I claim as my invention is:—

1. The combination with a shouldered support and a trimming material overlying said shoulder, of an anchorage strip having an offset anchorage portion for receiving a cover strip and a projection extending laterally from one of the longitudinal edges of said anchorage portion and cooper- 110

ating with said shoulder for securing said trimming material in place.

2. The combination with a shouldered support and a trimming material overlying said shouldered support, of an anchorage strip provided with transversely spaced longitudinally extending shoulders and with a projection extending laterally from adjacent

one of said shoulders, said projection cooperating with said shouldered support to secure said trimming material in place, the shoulders of said anchorage strip being adapted to receive with snap-on engagement a cover strip. 10

In testimony whereof I affix my signature.
HOMER G. KELLOGG.
